UNITED STATES PATENT OFFICE.

ALBERT H. TINNERMAN, OF CLEVELAND, OHIO.

STOVE-LEG CONNECTION.

Application filed February 4, 1927. Serial No. 165,834.

This invention relates to stove construction and more particularly to means for locking the leg of a stove to the frame. In modern stove construction a sheet metal band extends 5 around the base of the frame. This strip has a comparatively thin surface along the bottom edge and hence considerable difficulty has been experienced in providing an effective means for clamping the stove leg in 10 place.

An object of the present invention, therefore, is to make a simple construction by means of which a stove leg may be readily attached to that type of stove which has a 15 band extending around the base of the frame. A further object is to make an attaching device which in addition to holding a stove leg in proper position may be utilized for securing the stove to a packing crate.

20 The preferred construction by means of which my invention is accomplished is illustrated in the drawings, wherein Fig. 1 shows diagrammatically a stove outline in plan view; Fig. 2 is a section taken on an enlarged scale on a plane indicated by the line 2—2 in Fig. 1; Fig. 3 is a horizontal section 25 through the attachment on a plane indicated by the line 3—3 in Fig. 2; Fig. 4 is a perspective view showing a part of a stove leg which is made in accordance with my invention; Fig. 5 is a vertical section through a 30 part of the stove showing the manner of attaching it to a crate; Fig. 6 shows a bolt retaining device in use, and Fig. 7 is a section illustrating a modification of the cross bar 35 construction.

A stove frame, indicated at 10, is illustrated as having a base band 11 which is attached thereto in the usual way. The band 40 is shown in the shape of a rectangle and as extending beneath the bottom of the frame, where it forms a seat against which the stove legs may engage.

Each stove leg has a pair of shoulders 12 which extend at right angles to each other, and are arranged to fit snugly against the base band. Each leg also has an inturned horizontal flange 13, which is provided with a notch 14, and into which a securing member shown as an eye-bolt 15 may extend. The under surface of the flanges adjacent the notch, is sloped upwardly from the normal plane of the flange, while the member 15 is so connected to the base band, that the direction of application of locking pressure extends obliquely to the vertical. In this way

the shoulders 12 are wedged securely against the bottom edge, and inner surfaces of the base band.

One construction for holding the securing member 15 in position embodies a cross bar 20 which extends diagonally between two intersecting sides of the base band, as shown in Fig. 3. The cross bar may be rigidly connected to the band in any suitable way, but the connection illustrated however is made by riveting over the ends of the cross bar against the outer surfaces of the base band. The eye-bolt is pivotally mounted on the cross-bar and has a wing-nut 22 which cooperates with the bolt to clamp the leg to the frame. In Fig. 7, the cross bar 20^a is attached to the frame by independent removable securing members which are ordinarily employed for holding the beading strip in place.

An important advantage of my invention is the fact that the stove can be locked in a packing crate for shipment when the legs are removed from the stove. To this end the bolts 15 may be passed through openings in part of the packing crate as illustrated in Fig. 5. This saves considerable time by eliminating the necessity and use of special clamping means between the stove and crate.

When the stove is removed from a crate and is about to be assembled it is desirable that all sharp projections beneath the bottom of the base band be eliminated, so as to prevent scratching of a surface over which the stove may be moved. Since the eye-bolts tend to assume a vertical position when the stove is removed from a crate, and therefore tend to scratch or mar the floor surface, I provide means associated with the frame for temporarily holding the bolts above the bottom of the base band. One form of such means comprises a flexible sheet metal strip 30, which is rigidly fastened to the inner surface of the base band 100 and is adapted to be bent upwardly, as indicated in Fig. 6 and to form a support onto which the eye-bolt may rest until the stove is assembled. After the assembly the member 30 may be bent backwardly to the original position.

A stove leg connection made in accordance with my invention is advantageous in that it permits an assembly to be made in an expeditious manner and insures an even distribution of clamping pressure against the sides of the base band. Moreover, the cross

bar construction, adjacent the corners, increases the rigidity of the assembled stove. A further important advantage of my invention is the fact that the eye-bolts which hold the stove legs in place may be utilized for clamping the stove to a packing crate. This obviates the necessity for special clamping devices.

Having thus described my invention, I claim:

1. The combination with a stove frame, of a cross-bar rigidly mounted thereon, and across a corner thereof, a stove leg, and means pivotally mounted on the cross-bar and adapted to be connected to the leg for clamping it to the frame.

2. In a stove, the combination with a base band arranged in the shape of a rectangle, of a member extending across the adjacent sides of the bands and being rigidly attached thereto, a stove leg, and means pivotally mounted upon said member and adapted to be attached to the leg for clamping it to said base band.

3. In a stove, the combination with a frame, of a base band associated therewith, said base band being in the shape of a rectangle, the stove leg having shoulders disposed at right angles to each other and adapted to engage the bottom and inner surfaces of two sides of said base band, a cross-bar extending diagonally between two of the sides, an eye bolt pivotally mounted on said cross-bar, and means associated with the eye-bolt for locking it to the stove leg.

4. In a stove, the combination with a hollow frame arranged in the form of a rectangle, a stove leg, means disposed inside the frame for clamping it to the stove leg,

said means including a member carried by the frame and extending downwardly and inwardly therefrom, whereby the direction of application of the clamping pressure extends obliquely to a plane passing through one of the frame sides.

5. In combination, a stove frame having vertical sides, a cross-bar connecting two of the sides and extending diagonally therebetween, a stove leg engaging the sides, and an eye bolt pivotally mounted on the cross-bar and adapted to be attached to the leg, said leg having an abutment against which the bolt may be engaged, whereby the direction of application of clamping pressure between the bolt and leg extends obliquely to a vertical line.

6. In a stove, the combination with a frame, of a stove leg, means for attaching the frame to the leg, said means including a member pivotally mounted upon the frame and adapted to engage said leg; and other means associated with the frame for engaging said member and holding it in a predetermined position above the bottom of the frame when the stove leg is disconnected from the frame.

7. In combination, a stove frame, a stove leg, means connecting the frame and leg, said means including a member pivotally mounted on the frame, and a flexible member associated with the frame and adapted to engage the first mentioned member for holding it in a predetermined position above the bottom of the frame when the leg is disconnected from the frame.

In testimony whereof, I hereunto affix my signature.

ALBERT H. TINNERMAN.
